UNITED STATES PATENT OFFICE.

CURTIS C. LILLIBRIDGE, OF HUTCHINSON, KANSAS.

FUEL FEEDER AND CUT-OFF.

1,334,251.

Specification of Letters Patent. Patented Mar. 16, 1920.

Application filed November 3, 1919. Serial No. 335,368.

To all whom it may concern:

Be it known that I, CURTIS C. LILLIBRIDGE, a citizen of the United States, residing at Hutchinson, in the county of Reno 5 and State of Kansas, have invented certain new and useful Improvements in Fuel Feeders and Cut-Offs; and I do declare the following to be a full, clear, and exact description of the invention, such as will enable others skilled in the art to which it 10 appertains to make and use the same.

This invention relates to improvements in liquid fuel burners, and it has more particular reference to a means for automatically cutting off the supply of fuel to the burner in case more fuel is running into the burner than is necessary.

The principal object of the invention is to improve upon Patent #1,243,194 granted to me on October 16, 1917, for a similar device. I have found from experience that my patented cut off mechanism could not be effectively and conveniently used to an advantage under all circumstances, especially 25 in connection with heating stoves. In other words, the patented device can not be effectively installed in small unhandy places. Therefore, as before stated, the present invention is designed to overcome the above 30 mentioned objection. That is, it is especially designed to be used in connection with any conventional type of heating stove, wherein space is generally limited and access to a device of this type generally difficult and very unhandy.

Another object of the invention is to provide a device of the above mentioned type which is simple in construction, yet highly efficient, one which is strong, durable, and inexpensive to manufacture.

Other objects and advantages of the invention will be apparent during the course of the following description.

In the accompanying drawings forming 45 a part of this specification and in which like numerals are employed to designate like parts throughout the same,

Figure 1, is a central vertical sectional view of a heating stove equipped with a device constructed in accordance with my invention.

Fig. 2, is an enlarged top plan view of my device.

Fig. 3, is a perspective view of one of the 55 details.

In the drawings, wherein for the purpose

of illustration is shown a preferred embodiment of my invention, the letter S designates a heating stove which includes a burner B, and an annular skirt or base C, 60 which is disposed below the burner.

My invention resides in a fuel supply pipe 1 which leads from a suitable tank 2 to the burner B. A portion of this pipe is disposed within the base or annular skirt C 65 and is provided with a supplemental cut off valve 3, which is normally retained closed by an overbalancing arm 4. This overbalancing arm may be of any suitable construction, but I prefer to construct it 70 like the one shown in my aforesaid patented device. That is, it consists of a cylindrical tubular member 5. This member 5 is secured to the handle of the valve 3, which in this instance is a hand wheel 6, by suitable 75 clip 7, which surrounds it and is soldered or otherwise secured to the wheel 6. This clip, like those in my patented device, is preferably disposed near one end of tubular member as shown, so that it will form in effect 80 a lever, as is obvious.

An overflow pipe 8 extends from the burner B downward and into an overflow receptacle or pan 9. Herein lies the improvement over my aforesaid patented device. That is this pan is of a different design and is so mounted that it may be conveniently emptied, will not be liable to tip over or spill, and is strongly mounted in position. This pan is preferably shallow 90 and it extends entirely beneath the valve 3, overflow pipe 8, and the delivery end of the supply pipe 1. Hence, it will be seen that any oil which might leak from any of these parts will be caught in the pan and 95 saved. Pan 9 is provided with a depending leg 10, which in this instance is a narrow metal plate which has its upper end bent over one edge of the pan and secured in any suitable manner. The lower end of the leg 100 is bent to form an eye or bearing 11, through which a rod 12 extends, the latter being supported by the base C, as shown. This construction permits the pan to swing on a pivot as it fills up. This pan is not designed 105 to be removed.

The short end of the overbalancing arm 4 is provided with a hook 13 on which the loop 14 of the pan 9 is hung. The weight of the empty pan is overbalanced by a metal ball 110 which is placed within the tubular member 5, and when this ball is at one end of the

member opposite to that carrying the hook 13, the parts will be in the position shown in Fig. 1. As soon as the weight of pan 10 and its contents becomes sufficiently great to 5 overbalance the member 5, the latter will be moved to a position to close the valve.

The essential difference between the present invention and that of the aforesaid patent is the fact that this device can be placed 10 in a smaller space, and to this end the pan is made more shallow. The location of the pan is another advantage, that is it extends beneath the valve, the overflow pipe and the delivery end of the supply pipe and catches 15 any and all oil which would otherwise be wasted. When in the position shown in Fig. 1, the pan is substantially rigid. This prevents it from accidentally tilting and spilling because of the manner in which it is 20 mounted. This construction also keeps the pan directly beneath the overflow pipe at all times. When it is desired to empty the pan, a suitable receptacle is placed beneath it. In my aforesaid patent it is generally necessary 25 to remove the overflow receptacle to empty it. This is a bad feature, in that when the receptacle is lifted off its supporting hook, the overbalancing arm again opens the valve and of course, if there should be 30 any overflow of oil, it would leak on the floor while the receptacle was being emptied. However, this bad feature is eliminated with the present device, as the pan is not designed to be removed.

35 It is to be understood that the form of my invention herein shown and described is to be taken as a preferred form of the same, and that various changes in the shape, size and arrangement of parts may be resorted 40 to without departure from the spirit of the invention or the scope of the subjoined claims.

Having thus described my invention, I claim:—

45 1. The combination with a burner of a

fuel supply pipe connected therewith, a cut off valve in said supply pipe, an overbalancing arm for actuating said valve, an overflow pipe from said burner, a shallow receptacle extending beneath valve, overflow 50 pipe and the delivery end of the supply pipe, means for pivotally mounting one edge of said receptacle, and means for supporting the opposite edge thereof from said overbalancing arm.

55 2. The combination with a burner, of a fuel supply pipe connected therewith, a cut off valve in said supply pipe, an overbalancing arm for actuating said valve, an overflow pipe from the burner, a shallow pan 60 extending beneath the valve, overflow pipe and the delivery end of the supply pipe, a depending leg carried by one edge of the pan, the lower end of said leg having a bearing, a rod for pivotally supporting said pan, 65 said rod extending through the bearing, and means detachably connecting the opposite edge of the pan to the balancing arm, substantially as set forth.

70 3. The combination with a stove, including a burner and a base, of a supply pipe, a portion of which is disposed within said base, a cut off valve in said supply pipe, an over balancing arm associated with said valve and adapted to hold the valve normally 75 open, an overflow pipe extending from said burner, a shallow pan extending beneath said valve, overflow pipe and the delivery end of the supply pipe, a depending leg connected to one edge of the pan, the lower 80 end of said leg having a bearing, a rod for pivotally supporting said pan, said rod extending through the bearing and being connected to said base and means for detachably connecting the opposite edge of the pan 85 to the balancing arm, substantially as set forth.

In testimony whereof I have hereunto set my hand.

CURTIS C. LILLIBRIDGE.
